GARMENT HANGER

Tecla C. Giacomelli, Hamilton, Ontario, Canada

Application June 16, 1950, Serial No. 10,561

Term of patent 14 years

(Cl. D80—8)

To all whom it may concern:

Be it known that I, Tecla C. Giacomelli, a citizen of Canada, residing at Hamilton, in the county of Wentworth and Province of Ontario, Canada, have invented a new, original, and ornamental Design for a Garment Hanger, of which the following is a specification, reference being made to the accompanying drawing, forming part thereof, and in which the single figure is a face view of a garment hanger showing my new design.

The garment hanger is thin and flat.

I claim:

The ornamental design for a garment hanger, as shown and described.

TECLA C. GIACOMELLI.
